GILBERT RIMMER, OF LONDON, ENGLAND, ASSIGNOR TO SULLIVAN MACHINERY COMPANY, OF CHICAGO, ILLINOIS.

COAL-CUTTING MACHINE.

Application filed June 21, 1922. Serial No. 569,860.

To all whom it may concern:

Be it known that I, GILBERT RIMMER, a subject of the King of England, residing in London, England, have invented certain 5 new and useful Improvements in Coal-Cutting Machines, of which the following is a specification.

This invention consists in improvements in or relating to coal-cutting machines of 10 a well-known type in which the machine hauls itself along a chain termed the "haulage-chain". The body or central section of the machine contains the source of power which generally is an air-driven turbine or 15 an electric motor. A front section attached to, or constituting one end of the body, contains the haulage mechanism and to or at the other end of the body is pivoted a jib capable of being slewed in a horizontal 20 plane when the machine is in operation.

Round the margin of the jib is driven an endless chain, termed the "cutter-chain", armed with cutting-tools or picks and travelling in a horizontal plane.

25 It is customary to utilize the haulage-chain, which is generally an ordinary loose-link chain, to slew the jib, and it is an object of the present invention to provide means for connecting the haulage-chain to the jib in such a manner that it will be prevented from sagging and fouling the fast-moving cutter-chain should the haulage-chain become slack while attached to the jib.

According to the present invention there 35 is employed for this purpose a bridging connector serving as a continuation of that end of the haulage-chain which is to be connected to the jib, means operatively to engage the connector with the jib, said connector being sufficiently inflexible in a direction towards the jib as to prevent it sagging in its own length so far towards the cutter-chain as to foul the latter and the length of the connector being so chosen that 45 both the connector and haulage-chain will be kept clear of the cutter-chain. Conveniently the connector comprises two or more links pivotally connected to one another end-to-end (such for example as pitch-chain or linkage) with the axis of pivoting transverse to the plane in which the cutter-chain moves. Alternatively the operative connection between the said bridging-connector and the jib is such that the length of

the connector is held approximately parallel to the plane in which the cutter-chain moves, for example by means of a squared end to the connector fitting a squared hole in the jib.

The foregoing and other features of the 55 invention will be more clearly understood from the following description of some preferred embodiments of the invention, given by way of example only, with the aid of the accompanying drawings, in which—

60 Figure 1 is a plan of the principal parts of the coal-cutting machine necessary for the understanding of the present invention;

65 Figure 2 is an elevation of the parts shown in Figure 1;

70 Figures 3 and 4 illustrate two detailed and specific constructions of the bridging-connector; and

75 Figure 5 is a view, on an enlarged scale, looking on the face of the hook of the connector illustrated in Figure 4, that is to say as viewed from above in that figure.

80 Like reference numerals indicate like parts in the drawings.

Referring to Figures 1 and 2, the body or central section of the machine is indicated at 10 and contains the source of power. The front section referred to, and indicated at 11, contains the haulage-mechanism, and at the other end a jib 12 is pivoted to slew 85 about an axis 13. The cutter-chain 14 is fitted with coal-cutting tools or picks 15 and the cutter-chain, with its tools or picks, travels round the margin of the jib in a horizontal plane when the machine is in 90 operation. The parts so far described are of ordinary and known construction.

95 In order to slew the jib 12, for example from the full-line position in Figure 1 to the diametrically opposite dotted-line position illustrated or to the intermediate dotted position in which the jib extends end-on from the body 10, it is customary to utilize the usual haulage-chain 16 of an ordinary loose-link character, that is to say a chain in 100 which each link is free to swing freely in relation to its companion links in various directions. Such a chain is flexible in each of two planes which are parallel and perpendicular to one another. This chain is utilized 105 generally with the aid of a double-ended hook (sometimes called a "clevis") the free end of the haulage-chain being engaged with

one end of that hook and the other end of the hook being engaged with a projection such as 17 on the jib at a point near the in-board or heel end of the latter and above the plane in which the cutter-chain travels. Upon this hook is generally provided a horizontally-projecting pin to lie in a notch in the middle of the upper side of the jib projection 17. This pin and notch serve, under ordinary circumstances, to keep up the double-ended hook and the adjacent portion of the haulage-chain that is connected to it, so that the end of the haulage-chain is held above the level of the cutter-chain. But though the construction so far described has been found to operate satisfactorily so long as the haulage-chain is kept taut, it has been found that it cannot be relied upon to prevent the loose-link haulage-chain from sagging and becoming foul of the fast-moving cutter-chain when the haulage-chain is slackened. This slackening is more or less unavoidable at times and it may for instance arise from breakage of the haulage-chain or from its slipping out of recesses in a wheel or one of the wheels (shown in the part 11 in Figures 1 and 2) which is or are operated to haul upon it by the aforesaid source of power in the machine. As a consequence of this fouling series damage to the machine from jamming the rapidly running cutter-chain and driving parts may result.

The foregoing description concerns the general construction, operation and defects of coal-cutting machines of this type as hitherto used, and it is the object, as before stated, of the present invention to prevent the possibility of the haulage-chain fouling the cutter-chain.

In the present invention there is provided, as the free end of the haulage-chain 16, a temporary or permanent length of chain 18 which, in the example illustrated in Figures 1-3, is a pitch-chain in which the pivoting of adjacent links to one another is constrained so that the chain is substantially only flexible in one plane, that is to say in a plane normal to the axes of pivoting of the links.

If desired there may be, as clearly shown in Figure 3, on the part of the pitch-chain which is near to that end of it which engages the jib, a horizontally-projecting pin 19 like that upon the "clevis" aforesaid to assist in keeping the free end of the pitch-chain horizontal. Beyond the pin 19 the chain 18 is formed with a hooked extremity 20 which engages with the side margin of the jib projection 17 and the pin 19 drops in a slot 21 formed inwardly from the upper edge of the projection 17. The co-operation of the hooked extremity 20 and the pin 19 with the parts of the projection 17 with which they engage serves to maintain the length of chain 18 in a substantially hori-

zontal position, that is to say parallel with the plane of the jib and cutter-chain. The length of the chain 18 is such that the other end of it, formed with a hook 22 to engage the loose-link haulage-chain, extends sufficiently far beyond the cutter-chain and its associated tools 15 that the chain 16, even should it become slack, will not foul the tools 15. This is shown clearly in Figure 2.

An alternative form of connector to replace the pitch-chain 18 is illustrated in Figures 4 and 5 and comprises a two-part linkage 23, 24 whereof the two parts are pivotally connected at 25. The part 24 herein is provided with a pin 19 and a similarly hooked portion 20 having a narrow nose 20^a adapted to be received in the chain slot 20^b on the machine frame, the connection of the parts being such that the member 24 will be held against objectionable swinging by the extremity 20^a and yet sufficient play will be present to permit the removal of the member 24 when desired. The part 23 is also shown to be formed at 22 with a means for attachment of it to the haulage-chain 16.

It will be understood that the connector comprising the pitch-chain 18 or the linkage 23, 24, though flexible in one plane, is stiff and virtually inflexible in any other.

The links of the pitch-chain 18 or the linkage 23, 24, may be so constructed and so engaged with one another that their flexibility, even in the one plane in which the chain or linkage is flexible, would be limited; that is to say so that the pitch-chain or linkage shall be free to curve as it winds round the end of the machine in slewing the jib but so that in coming off the curved portion it shall uncurve into, say, a straight line and no further. This constitutes an additional precaution against the sagging or movement of the chain into undesirable positions.

Alternatively the free end of the connector may enter and fit a hole in the projection 17 so shaped (e. g. squared) as to limit the movement of the connector in relation to it in such a way that the connector shall not move out of the horizontal plane of its engagement with the jib to any material extent. Thus, a projecting pin such as 19 may be squared to fit into a squared hole or recess such as is suggested above as an example.

A further alternative may be to substitute the pitch-chain or linkage by a single-piece rigid connector of such length that even should it slew about its connection with the jib (for example about the axis of the pin such as 19) to such an extent that that end of it connected to the loose link chain rests on the ground or surface upon which the cutting-machine is operating, the connector will still be in a position clear of the tools 15 of the cutter-chain. Such a connec-

tor need not be of the length above described if means are afforded by which the slewing of the connector is prevented.

- The employment of a bridging-connector 5 in any one of the forms according to this invention is a cheap and simple means of preventing the free end of the haulage-chain constituted thereby from fouling the cutter-chain. The construction of these coal-cutting machines is such that it has not been found to be practicable to employ, for the constraint of the jib-actuating end of the haulage-chain, any projections from the machine itself.
- 15 While I have in this application specifically described certain forms which my invention may assume in practice, it will be understood that these forms of the same are shown for purposes of illustration and that 20 the invention may be modified and embodied in various other forms without departing from its spirit or the scope of the appended claims.
- 25 What I claim as my invention and desire to secure by Letters Patent is:—

1. A mining machine including in combination, a pivoted cutter bar having cutters thereon, flexible means connectible to swing said bar, and flexible means connectible 30 thereto and to the bar and extending over the latter for inhibiting conflict of said means with said cutters.

2. A mining machine including in combination, a pivoted cutter bar having cutters thereon, flexible means connectible to swing said bar, and flexible means connectible thereto and to the bar and extending over the latter for inhibiting conflict of said means with said cutters, said last 40 mentioned means moving angularly with said bar.

3. A mining machine including in combination, a pivoted cutter bar having a cutter chain thereon, and flexible means connectible to swing said bar, and flexible means connectible thereto and to the bar and extending over the latter for inhibiting conflict of said means with said chain said last 50 mentioned means being non-flexible vertically.

4. A mining machine including in combination, a pivoted cutter bar having a cutter chain thereon, and flexible means connectible to swing said bar, and flexible means connectible thereto and to the bar and extending over the latter for inhibiting conflict of said means with said chain, said last mentioned means being non-flexible vertically and movable angularly with said bar.

5. A mining machine comprising a 60 pivotally connected cutter chain carrying cutter bar and a flexible feeding member, and articulated means extending over said cutter chain between said member and bar for preventing fouling between said mem-

ber and said cutter chain, the articulations in said means having vertical axes.

6. A mining machine including a pivoted cutter bar and cutters thereon, and means for swinging said bar about its pivot including a flexible feeding member and a flexible connection between the latter and said bar inflexible in a direction toward said cutters.

7. A mining machine including a pivoted cutter bar and a cutter chain on the latter, and means for swinging said bar about its pivot including a flexible feeding member and a flexible connection between the latter and said bar inflexible in a direction toward 75 said bar, and movable angularly with said bar.

8. A mining machine including a pivoted cutter bar, and a cutter chain on the latter, and means for swinging said bar about its pivot including a flexible portion and a supplemental sectional portion connectible to said flexible portion and said bar and having provision for preventing conflict with 80 said cutter chain.

9. A mining machine including in combination, a pivoted cutter bar having cutters thereon, flexible means connectible to swing said bar, and means for inhibiting conflict of said flexible means with said cutters including a flexible bridging connector serving as a continuation of said flexible means, said connector comprising means operatively to engage said connector with 90 said bar, and means preventing the flexible of said connector in a direction towards the bar.

10. A mining machine including in combination, a pivoted cutter bar having cutters thereon, flexible means connectible to swing said bar, and means for inhibiting conflict of said flexible means with said cutters including a flexible bridging connector serving as a continuation of said flexible means, said connector including means operatively to engage said connector with said bar, in a direction towards the bar, and means for keeping slack in said flexible means away from the bar.

11. A mining machine including in combination, a pivoted cutter bar having cutters thereon, flexible means connectible to swing said bar, and means for inhibiting the conflict of said flexible means with said cutters including an articulated bridging connector connected between said flexible means and bar comprising a plurality of links pivotally connected to one another end to end with the axis of pivoting transverse to the plane in which the cutters move.

12. A mining machine including in combination, a pivoted cutter bar having cutters thereon and having a portion provided with an aperture, flexible means connectible to swing said bar, and means for inhibiting 130

- conflict of said flexible means with said cutters including a flexible bridging connector connected between said flexible means and bar, and means operatively to engage said connector with said cutter bar including a projecting portion formed on the connector cooperating with the aperture in the apertured portion of the bar whereby the length of the connection is held approximately parallel to the plane in which the cutters move.
13. A mining machine including a pivoted cutter bar and a cutter chain on the latter, said machine having a portion providing a slot in a plane substantially parallel to the plane of bar swing, and means for swinging said bar about its pivot including a flexible portion and a supplemental sectional portion connectible to said flexible portion and said bar, and having provision for preventing conflict with said cutter chain including means for preventing flexing of said sectional portion in one direction and means engageable with said machine comprising an inwardly projecting portion formed on said sectional portion and engageable in said slot.
14. A mining machine including a pivoted cutter bar, and a cutter chain on the latter, and means for swinging said bar about its pivot including a flexible portion and a supplemental sectional portion connectible to said flexible portion and said bar and having provision for preventing conflict with said cutter chain including means for preventing flexing said sectional portion in one direction and means engageable with said machine.
15. A mining machine including a pivoted cutter bar, and a cutter chain on the latter, and means for swinging said bar about its pivot including a flexible portion and a supplemental sectional portion connectible to said flexible portion and said bar and having provision for preventing conflict with said cutter chain including means for preventing flexing said sectional portion in one direction and means engageable with said machine and including a pin carried by one section thereof.
16. A mining machine including a pivoted

cutter bar and a cutter chain on the latter, said bar having an upstanding abutment thereon means for swinging the bar about its pivot including a flexible portion, and a supplemental sectional portion connectible between said flexible portion and the upstanding abutment formed on said bar and having provision for preventing conflict with said cutter chain including means for preventing flexing of said sectional portion in a direction toward the plane of movement of said cutter chain.

17. A mining machine including a pivoted cutter bar and a cutter chain on the latter, and means for swinging said bar about its pivot including a flexible feeding member and a flexible connection comprising a closed link chain disposed between the latter and said bar and inflexible in a direction toward said bar and cutter chain.

18. A mining machine including a cutter bar movable in a substantially horizontal plane and a cutter chain thereon, means for moving said cutter bar including a flexible feeding member, and means comprising a flexible bridging connector extending over and beyond the path of the cutter chain and attachable to the machine and to said flexible feeding member, said connector comprising means for inhibiting conflict of said flexible feeding member with said cutter chain.

19. A bridging connector for use as described consisting of an elongated middle portion flexible in one plane and virtually inflexible in a plane perpendicular to said first plane and end pieces provided respectively with means adapted for connection to a part on a mining machine and to haulage means.

20. A bridging connector for use as described consisting of a plurality of articulated links flexible in one plane and virtually inflexible in a plane at right angles to said first plane, the end links being provided respectively with means adapted for connection to a part on a mining machine and to haulage means.

In testimony whereof I affix my signature.

GILBERT RIMMER.

Certificate of Correction.

It is hereby certified that in Letters Patent No. 1,571,161, granted January 26, 1926, upon the application of Gilbert Rimmer, of London, England, for an improvement in "Coal-Cutting Machines," errors appear in the printed specification requiring correction as follows: Page 3, line 48, claim 3, after the word "chain" insert a comma; same page, line 111, claim 10, after the word "bar" insert the words *means preventing the flexing of said connector*; page 4, line 53, claim 16, after the word "thereon" insert a comma; same page, line 68, claim 17, for the word "later" read *latter*; and that the said Letters Patent should be read with these corrections therein that the same may conform to the record of the case in the Patent Office.

Signed and sealed this 2d day of March, A. D. 1926.

[SEAL.]

M. J. MOORE,
Acting Commissioner of Patents.
